UNITED STATES PATENT OFFICE.

GILBERT F. FLETCHER, OF BANGOR, MAINE.

BANKER.

1,409,163.

Specification of Letters Patent.

Patented Mar. 14, 1922.

Application filed February 3, 1920. Serial No. 356,057.

To all whom it may concern:

Be it known that I, GILBERT F. FLETCHER, a citizen of the United States, and resident of Bangor, in the county of Penobscot and

5 State of Maine, have invented certain new and useful Improvements in Bankers, of which the following is a specification.

10 My invention relates to bankers, and is designed to improve means for supporting 15 the material from which monuments, statues and the like are fashioned.

It is usual in monumental work to have a support upon which the stone or material to be operated upon is placed, and means is 15 provided for raising or lowering said support to position it so that it may be operated upon by the monumental worker more easily.

20 It is one of the objects of my invention to provide a support of this sort, which can be easily and quickly raised to the desired height and thereafter secured in such adjusted position, but allowing the support to be rotated to eliminate the necessity of the operator changing the position at which he is 25 working. This feature is very important, as it is oftentimes necessary to work from one particular point in order that proper light may be thrown upon the work.

30 With my invention these features have been accomplished, as I provide a support which may be quickly and with a small amount of effort raised to any desired height and thereupon secured. In its adjusted positions, my support is adapted to be rotated by the operator so that the work may be turned as the operator desires.

35 With these and other features in mind, I will more specifically describe and point out the essential details of my invention in the specification, and in drawings, in which,—

40 Fig. 1 is a sectional view of my device, with certain parts in elevation;

45 Fig. 2 is a transverse sectional view on line 2—2 of Fig. 1; and

Fig. 3 is fragmentary view of a modified form of my device.

50 In the drawings, referring more particularly to Fig. 1, numeral 1 indicates the flooring upon which my device is secured, and 2 the wall thereof. The work is adapted to be supported upon a table 3, rigidly secured to a standard 4. This standard 4 is here 55 shown in the form of a piston rod, having

secured at its lower end a piston head 5. I provide a piston cylinder 6, in which said head 5 and rod 4 are adapted to work.

In this form of the device I prefer to use fluid pressure means for raising the table 3, and in carrying out this feature of my invention I provide a pipe 7, secured to the wall 2 adjacent the support in any suitable manner. To this pipe the source of fluid pressure (not shown) may be connected. A control valve 8 controls the admission of the fluid pressure to the pipe 7.

The pipe 7 extends beneath the flooring 1 and into the box-like compartment 9, which encloses the piston cylinder 6 and the air pressure connections thereto. The fluid pressure pipe 7 terminates immediately adjacent the lower end of the cylinder 6 and is connected to a T-coupling 10. A short pipe 11 extends from one side of this T-coupling 75 10 and connects the source of fluid pressure to the lower end of the cylinder 6. A valve 12 is connected to the lower end of the T-coupling 10 for the purpose of discharging any collection of sediment or foreign matter 80 which may collect in the lower end of the cylinder 6.

A vent port 13 is positioned at the top of the cylinder 6. This vent port is always open, allowing communication between the 85 inside of the cylinder 6 and the atmosphere. The purpose of this vent will be readily seen, as it is necessary to allow the escape of the air in the upper portion of the cylinder 6 when the piston head 5 is raised, and also, it 90 is necessary to break the vacuum, which will occur in the upper portion of the cylinder 6 when the piston head 5 is lowered.

I wish to provide an exhaust valve 14 in the pipe 7 between the control valve 8 and 95 the cylinder 6, for the purpose of exhausting the air beneath the piston head 5 when it is desired to lower the support 3. It is obvious that this valve 14, together with the valve 8, may be put at any desired place, but 100 I preferably place them in the position shown in Fig. 1 of the drawings, so that they may be conveniently operated.

It is obvious from the foregoing description that when I desire to raise the support 105 3, it is merely necessary for me to admit fluid pressure to the pipe 7 by means of the valve 8, which fluid pressure, operating upon the piston head 5, raises the support 3. When the desired height has been reached I 110

wish to secure the support in its adjusted position without relying upon the fluid pressure. To accomplish this purpose I have provided a split collar 15, which encircles the standard 4 and is secured in position by bolts and nuts 16.

- In order to provide a bearing for this collar 15 I use a bushing 17, which surrounds the support 4 and rests upon the floor 1.
- 10 This bushing member is shaped to form a bearing rim 18, upon which the split collar 15 is adapted to rest. When the collar 15 has been clamped to the standard 4 it will support the weight of the monument or work 15 operated upon, such weight being supported directly upon the rim 18. It is therefore, obvious that the standard 4 may be rotated and the collar 15 will bear upon the rim 18 and support the standard thereby.
- 20 For the purpose of gaining access to the compartment 9, I provide an opening 19 through which the operator may reach to control the valve 12 when it is desired to discharge sediment, etc., from the lower end of 25 the cylinder 6.

Referring now more particularly to the modified form of my device, shown in Fig. 3, it will be seen that the standard is in the form of a screw-threaded shank 20, supported in an internally-threaded sleeve 21. This sleeve 21 is formed integrally with a collar member 22. This collar member is secured to the floor 1 by means of bolt and butts 23. The work is supported upon a 30 turn-table 24 adapted to revolve upon the supporting plate 25, rigidly secured to the upper end of the standard 20. Handles 26 are provided for rotating the plate 25, and consequently the standard 20, to raise 35 or lower the support to any desired position.

In order to provide means for securing the standard 20 in any of its adjusted positions, I provide a set screw 27, controlled by a handle member 28, which has a swivel 45 connection 29 with the set screw 27. By this it is apparent that the set screw 27 may be operated from a distance to eliminate the necessity of stooping under the table 24 to operate this set screw.

- 50 Thus, it will be seen that with this form of my device when it is desired to raise the work supported by the turn-table 24, it is only necessary to grasp the handles 26 and rotate the standard 20, which, by reason of 55 its screw-threaded connections with sleeve 21, will be slowly raised. When the desired height has been reached, the set screw 27 may be adjusted by the handle 28 to bind the standard 20 and thereby hold it rigidly 60 in its adjusted position. As hereinbefore mentioned, the table 24 is of any ordinary turn-table construction, and therefore, when it is desired to rotate the work, this may be easily done by merely grasping the work 65 and turning it to the desired position, the

plate-like support 25, which is rigid with the standard 20, of course remaining stationary.

From the foregoing it is seen that I have provided a support which embodies all of the desired features for a device of this character. The block of granite or work to be operated upon may be placed upon the supporting table and the table raised to any desired height. The standard then, 75 upon which the table is mounted, may be locked in its adjusted position to more thoroughly insure the stability of the device, and thereafter any rotary adjustments which the operator may desire may be made by 80 reason of the oscillating connection between the standard and the bushing in the preferred form, and the turn-table and its support in the modified form. In lowering the work, in the preferred embodiment of my 85 invention, it is necessary, first, to loosen the split collar 15 and then operate the valve 14 to allow the escape of the air, or other fluid pressure from the lower end of the cylinder 6. By doing this it will be seen 90 that the work of its own weight will force the piston to its lowermost position in the cylinder.

In the modification the process of lowering is slightly different. The set screw 27 is 95 first loosened and then, by rotating the standard 20, it may be lowered to any position.

I have described and shown two forms of my invention, but it will be apparent that 100 various changes and modifications from the specific structure may be resorted to without departing from the spirit and scope of my invention.

Having thus described my invention, what 105 I claim is:

1. In a device of the class described, a work supporting table, a standard rigidly secured thereto, a piston head on said standard, a cylinder, means for admitting fluid 11 pressure to the lower end of said cylinder and under said piston head for raising said table, a flooring for supporting said device, a bushing adapted to form a bearing rim secured to said flooring, a split collar 11 encircling said standard and adapted to be clamped upon said standard to support the table in its adjusted positions and bearing upon said supporting rim, as and for the purpose set forth.

2. In a banker of the class described the combination with a floor of a work supporting table adapted to be moved to a point adjacent the floor, a standard secured to said table and projecting through said floor, 1 a piston head on said standard and a cylinder beneath said floor in which said piston head works for elevating said table, a bearing rim secured to the top side of said floor and means adjustable on said standard and 1

co-operating with the bearing rim to retain the table in its elevated positions.

3. In a banker of the class described the combination with a floor of a work supporting table adapted to be moved to a point adjacent the floor, a standard secured to said table and projecting through said floor, a piston head on said standard and a cylinder beneath said floor in which said piston head 10 works for elevating said table, a bearing rim secured to the top side of said floor through which said standard projects, and a split collar encircling the standard and adapted to be clamped thereon to retain the table in 15 its adjusted positions by abutting the bearing rim, substantially as described.
4. In a banker of the class described the combination with a floor of a work support-

ing table adapted to be moved to a point adjacent the floor, a standard rigidly secured 20 to said table and projecting through said floor, a piston head on said standard, a cylinder beneath said floor in which said piston head works for elevating said table, means for admitting fluid pressure to said cylinder 25 for raising said table, means for exhausting the air from said cylinder, a bearing rim secured to the top side of said floor through which said standard projects, and a split collar encircling the standard and adapted 30 to be clamped thereon to retain the table in its adjusted position by abutting the bearing rim thereby enabling said standard and table to be revolved, as and for the purpose set forth.

GILBERT F. FLETCHER.
